LOOM SHUTTLE

Isaac Snow, Lawrence, Mass., assignor to Draper Corporation, Hopedale, Mass., a corporation of Maine

Application September 3, 1935, Serial No. 38,903

8 Claims. (Cl. 139—215)

The present invention pertains to automatically threading loom shuttles and more particularly relates to tension devices for such shuttles.

Loom shuttles of the type to which my invention pertains are commonly comprised of a shuttle body having a bobbin-receiving cavity wherein is housed a package of filling, and automatically threading thread delivery means. The thread delivery means is usually constructed to apply tension to the running filling thread, the type of tension applying means employed being varied in accordance with the character of the filling. In some instances the filling can be adequately tensioned merely by the friction induced by contact with the guide walls or surfaces of the thread delivery means, while in other instances substantially greater tension is required. The present invention seeks to provide tensioning means capable of providing the said greater tension, but without resort to spring clamp tensions or other devices involving delicate moving parts.

I find that adequate tension for the running filling can be provided by a single stationary member in the form of a finger or post, but only if the filling makes at least one complete turn about such member. I have accordingly provided an automatically threading loom shuttle having thread delivery devices, a thread tensioning member of the type mentioned, and guiding means which operates automatically, and by virtue of the threading movement of the filling, to form the running filling into a closed loop the bight of which extends completely about the tensioning member. The specific embodiment shown on the drawing comprises a tensioning finger, having one end fixed and its other end free, and guiding means which forms the filling into a closed loop and guides the same onto the finger over the free end of the latter.

The preferred embodiment of the invention is illustrated on the accompanying drawing, of which:

Fig. 1 is a plan view of the thread delivery end of the shuttle comprising said embodiment, the filling thread being shown in the position it occupies at the start of the automatic threading operation;

Fig. 2 is a view similar to Fig. 1 but showing the filling at a later stage in the threading operation; and

Figs. 3 and 4 are, respectively, rear and end elevations of the threading block of Fig. 1 detached from the shuttle.

55 The shuttle shown on the drawing includes a

shuttle body 1 generally of conventional construction, the same having a bobbin-receiving cavity 2 in which is housed a filling carrier, as bobbin 3. The bobbin is adapted to be automatically ejected from the shuttle and replaced by a fresh one in the usual manner. The transfer of a fresh bobbin occurs, as is well-known in the art, while the shuttle is boxed, and a filling end *f* extends from the newly transferred bobbin longitudinally over the shuttle and is fixed to a 10 suitable holder, not shown.

The shuttle is provided with suitable thread delivery means of the type wherein the running filling becomes automatically threaded upon the picking of the shuttle first in one direction and 15 then in the opposite direction. The specific delivery means shown on the drawing includes a threading block 4 which has a longitudinal thread passage 5. The floor 6 of the thread passage is formed in the threading block, as is the front 20 wall 7 thereof. A thread guard 8 is preferably formed integrally with the wall 7 and projects outwardly and rearwardly therefrom over the thread passage. Immediately after the transfer of a fresh bobbin to the shuttle, the shuttle is 25 picked toward the left, Fig. 1. The filling during this first pick after transfer swirls about in unwinding from the bobbin and thus passes down into the thread passage 5 and beneath the guard 8, in the usual manner. The threading is completed upon the picking of the shuttle in the opposite direction, the filling thereafter emerging from the side delivery eye 9, as will be hereinafter 30 more fully explained.

The present invention provides a thread tensioning member, which may be comprised of a finger 10, about which the filling is to be looped. The specific finger 10 shown on the drawing is generally of cylindrical cross-section. It is positioned at the outer end of the thread passage 5, 40 outwardly of the shuttle from the guard 8. The finger has its lower end fixed in the floor 6 and extends upwardly and outwardly from the floor approximately normal to the path of the running filling. The upper end of the finger is free, 45 and may be reduced in size or pointed, for a purpose which will become apparent. The invention further provides guiding means for automatically causing the filling to become wrapped completely around the tensioning finger. 50

In the specific form shown, the guiding means is comprised of a plate 11 which, for convenience, may be formed integrally with the threading block. The plate is positioned over and spaced above the free end of the finger 10 and extends 55

to the rear thereof. The rearward edge of the plate is curved downwardly as at 12 to a point below the top of the finger. It will be noted that the filling, during the first pick after transfer, 5 swirls beneath the guide 11 and to the front of the finger 10, at which time it occupies the position in which it is shown by Fig. 1. Were the guide 11 not provided, the filling at the beginning of the second pick after transfer would merely 10 slide down the passageway 13 into the side delivery eye 9. However, the outer edge 14 of the guide intercepts the filling and forms it into a loop. That is, the guide edge 14 is curved rearwardly and inwardly from the point 15 where it 15 engages the filling at the beginning of the second pick after transfer. This curved guide edge is operative, by virtue of the threading movement of the filling toward the side delivery eye, to carry the filling rearwardly and thus form it into a 20 closed loop the bight of which extends completely about the tensioning finger.

The loop formed by the guide is "closed" in the sense that the legs of the bight, when viewed in plan, intersect, and it is in this sense that the 25 term "closed loop" is used in the appended claims. The loop is first formed by the guide substantially free of the tensioning finger, as in Fig. 3. Then, as the shuttle continues its movement, the 30 loop is guided onto the finger over the free end thereof as is indicated by Fig. 2. When the filling has completed its final threading movement so as to emerge from the side delivery eye 9, the 35 loop has passed down the tensioning finger and has become tightened, thus frictionally engaging the finger.

The wrapping of the running filling completely around the tensioning finger provides more friction than would otherwise be obtainable from a fixed tensioning member. The finger 10 may be 40 quite smooth, and thus the desired filling tension is obtained without danger of abrading the filling or breaking the strands or filaments thereof.

The loop forming guide means of the present 45 invention operates automatically by virtue of threading movements of the filling which are incidents of the operation of the conventional bobbin changing loom. Such movements of the filling are to be distinguished from the swirling movement of the filling in unwinding from the 50 bobbin. The latter movement has been utilized to cause the filling to wrap helically around a wire, as in Patent 1,785,223, Dec. 16, 1930, for example. The advantages of the present construction over such prior devices will be obvious.

55 Having fully disclosed the preferred embodiment of my invention, I claim:

1. An automatically threading loom shuttle having a bobbin-receiving cavity, a threading block having a longitudinal thread passage and 60 a thread guard projecting over said thread passage, a side delivery eye communicating with said thread passage, a thread tensioning member in said thread passage outwardly of the shuttle from said thread guard, and thread guiding means automatically forming the running filling into a 65 closed loop the bight of which extends completely about said tensioning member in frictional engagement therewith.

2. An automatically threading shuttle for 70 bobbin changing looms, said shuttle having a bobbin-receiving cavity, a threading block having a longitudinal thread passage into which the running filling becomes automatically threaded during the first pick after transfer, a side delivery eye into which the running filling becomes 75

automatically threaded during the second pick after transfer, a thread tensioning finger carried by said threading block, and a guide means carried by the shuttle in position to intercept the running filling as it threads toward said side delivery eye, said means being operative by virtue of the last said threading movement to automatically form the running filling into a closed loop the bight of which extends completely about said tensioning finger. 10

3. An automatically threading loom shuttle having a bobbin-receiving cavity, a threading block having a longitudinal thread passage, a side delivery eye communicating with said thread passage, a thread tensioning finger fixed in said 15 threading block and extending approximately normal to the path of the running filling through said thread passage and side-delivery eye, and guide means carried by the shuttle and engaging the running filling during the threading operation and automatically operable by virtue of such operation to wrap the running filling around said finger at least one complete turn. 20

4. An automatically threading loom shuttle having a bobbin-receiving cavity, a threading block 25 having a longitudinal thread passage, a side delivery eye communicating with said thread passage, a thread tensioning finger fixed in the floor of said thread passage and extending upwardly and outwardly from said floor, the upper end of 30 said finger being free, and a thread guide carried by said threading block and extending over said finger, said guide being curved to engage the running filling during the threading operation and form the filling into a closed loop the bight 35 of which extends completely about said tensioning finger in frictional engagement therewith.

5. An automatically threading loom shuttle having a bobbin-receiving cavity, a threading block having a floor and a front wall defining 40 a longitudinal thread passage, a thread guard projecting from said front wall outwardly and rearwardly over said thread passage, a side delivery eye communicating with said thread passage, a thread tensioning finger fixed to said 45 floor outwardly of said thread guard, said finger projecting upwardly and outwardly from said floor, and a thread guide carried by said threading block and extending over the upper end of said finger, said guide being curved to engage the 50 running filling during the threading operation and form the filling into a closed loop the bight of which extends completely about said tensioning finger in frictional engagement therewith.

6. An automatically threading loom shuttle 55 for bobbin changing looms, said shuttle having a bobbin-receiving cavity and thread delivery means of the type wherein the running filling automatically threads upon the picking of the shuttle first in one direction and then in the opposite direction, a thread tensioning finger carried by said shuttle, and means carried by the shuttle and operative upon the picking of the shuttle in the last said direction to automatically form the running filling into a closed loop the 60 bight of which extends completely about said finger in frictional engagement therewith.

7. An automatically threading loom shuttle for 70 bobbin changing looms, said shuttle having a bobbin-receiving cavity and thread delivery means of the type wherein the running filling automatically threads upon the picking of the shuttle first in one direction and then in the opposite direction, a thread tensioning finger fixed 75 in said shuttle and extending approximately nor-

mal to the path of the running filling in said delivery means, and guide means carried by said shuttle and operative upon the picking of the shuttle to wrap the filling around said finger at least one complete turn.

8. An automatically threading loom shuttle for bobbin changing looms, said shuttle having a bobbin-receiving cavity and thread delivery means of the type wherein the running filling 10 automatically threads upon the picking of the

shuttle first in one direction and then in the opposite direction, a thread tensioning finger having one end fixed in said shuttle and its other end free, and guide means carried by said shuttle and operative upon the picking of the shuttle in the last said direction to form the running filling into a closed loop and guide said loop onto said finger over the free end of the latter.
